MEDICATED DECONGESTANT INHALER

J. Allan McDonald, 440 Abbeyville Road,
Pittsburgh, Pa. 15228

Filed Aug. 9, 1974, Ser. No. 496,291

Term of patent 14 years

Int. Cl. D24—04

U.S. Cl. D83—1 N

FIG. 2

FIG. 1

FIG. 3

FIG. 4

FIG. 1 is a side elevation view of a decongestant inhaler showing my new design.

FIG. 2 is a rear elevation view thereof.

FIGS. 3 and 4 are respectively top and bottom plan views thereof.

I claim:

The ornamental design for a medicated decongestant inhaler, as shown and described.
